FIG. 2

UNITED STATES PATENT OFFICE

2,676,624

GUIDE CARRIAGE FOR POWER-DRIVEN
HAND TOOLS

Arthur C. Geemen, San Jose, Calif.

Application July 28, 1951, Serial No. 239,089

9 Claims. (Cl. 143—43)

1

The present invention relates to a tool guide, and pertains more particularly to a guide carriage for a power driven hand tool.

In present day woodworking practice, such as carpentry, cabinet making and pattern making, many of the older type hand tools such as, for example, saws, planes and sanders, have been supplemented, and in some cases almost supplanted by electrically driven counterparts.

For general use these hand held power tools require no accurate guiding beyond that which a skilled operator is capable of giving, but at times it is desirable to be able accurately to guide such tool from an established edge of a work piece upon which the tool is to be used.

The present invention contemplates the provision of an improved guide carriage for a power driven hand tool. It is also an object of the invention to provide a roller supported guide for hand tools wherein supporting rollers are mounted on portions of an adjustable guide element.

In accordance with one feature of the invention, there is provided a frame adapted to receive and retain the power tool to be guided, the frame having a supporting roller mounted at each end thereof upon shafts which comprise portions of a laterally extending, adjustable guide element adapted to engage an edge of a work piece for guiding the tool supported in the frame along a path a predetermined distance from, and parallel to said edge.

A device embodying the invention is illustrated in the accompanying drawings, wherein:

Fig. 1 is a perspective view of a tool guiding device embodying the invention as it would appear in operative position on a board, the position of a power driven hand saw when mounted in the device being shown in broken lines, as is also an alternately adjusted position of a guide element of the device.

Fig. 2 is a longitudinal vertical sectional view taken along line 2—2 of Fig. 1, the saw being shown in position in the guide.

Figure 3 is an enlarged fragmentary sectional view taken along line 3—3 of Fig. 1.

Fig. 4 is an enlarged fragmentary perspective view of a clamp screw for securing the rear end of the power tool in the guide frame.

Fig. 5 is an enlarged fragmentary exploded perspective view of a front end portion of a frame corner portion, the transverse front frame member being disconnected from the side angle member.

Referring to the details of the accompanying

2

drawings, the rectangular frame A has parallel longitudinal side members 10 and 11 of angle metal secured in laterally spaced relation by U-shaped front and rear transverse frame members 12 and 13 respectively. The side frame members 10 and 11 are mounted with lower flanges 14 thereof extending inwardly into the frame A. The front portion of each bottom flange 14 is severed from the vertical side flange 15 of its angle member (Figs. 1, 2 and 5) and is bent first upwardly at right angles at 17 (Figs. 2 and 5) and then rearwardly at 18 to form a hook-shaped, reversely bent portion 19. This reversely bent portion 19 is adapted to receive therebeneath, a portion of the tool to be mounted in the frame A, such as the upwardly bent forward end of a skid plate 20 of a power driven hand saw B. The side frame members 10 and 11 are spaced apart to receive the skid plate 20 therebetween so as to support the skid plate on the bottom flanges 14 of the angle metal side members 10 and 11. The distance between the hook-shaped retaining portions 19 and the rear U-shaped end members 13 is such as to receive the skid plate 20 closely therein.

A pair of supporting rollers 21 and 22 are mounted within end recesses in the frame A provided by the U-shaped end members 12 and 13. The rollers are mounted to rotate freely co-axially of parallel rod portions 23 and 24 of a laterally extending guide frame C. The parallel rod portions 23 and 24 of the guide frame C are inserted through aligned pairs of holes 25 in the sides of the recessed front and rear portions, respectively, of the frame A. The rod portions 23 and 24 are connected together by a downwardly and inwardly bent guide shoe portion 26. The shoe portion 26 is continuous with the rods 23 and 24, and is disposed at right angles thereto. The guide shoe portion 26 is adapted to ride along the edge of a work piece, such as a board D, to guide a tool in the frame A along a path located a predetermined distance from the edge of the work piece D engaged by the shoe 26, and parallel thereto.

The rollers 21 and 22 are mounted to rotate on friction reducing bushing 27, 27 (Fig. 2) the bores of which are adapted to receive telescopically the rod portions 23 and 24 respectively. If desired, the bushings 27, 27 may have their ends secured to the frame A to provide hollow axles for supporting the rollers 21 and 22 when the guide frame C is removed from the frame A.

For holding the rod portions 23 and 24 in axially adjusted position, a pair of clamp assem-

blies 28 and 29 are provided at the front and rear ends, respectively, of the frame A. Each of these clamp assemblies, as best shown in Fig. 3, comprises a plate portion 30 fixedly secured by rivets 31, 31 to a side of the frame side member 10. An internally threaded bushing 32 is provided on the outer end of the plate 30. The outer end portion of the plate 30 is reduced in width at 30a to slightly less than one-half the width of the vertical flange of the angle member 10 upon which it is mounted.

A swiveled clamping plate 33 is pivotally mounted, by means of a rivet 34, on the side of the plate 10 above the reduced forward portion 30a of the plate 30. A bushing 35 is welded to the outer end of the plate 33 to receive the shank of a thumb screw 37 therein. The lower portion of the thumb screw shank is threaded, and is screwed into the internally threaded bushing 32. Notches 36 and 39 are provided in the plates 30 and 33, respectively, to receive the rod portions 23 and 24 therein. Loosening the thumb screw 37 frees the rod portion 23 and 24 for movement to axially adjusted position so as to locate the guide shoe 29 a required distance from the side of the frame A. Screwing down the thumb screws 37 draws the pivoted plates 33 toward the plates 30 and thereby clamps the rod portions 23 and 24 in adjusted position.

In using the device, it is simply necessary to insert the power tool B in the frame A as shown in Fig. 1. This is accomplished by tilting the forward end of the power tool downwardly to introduce the up-curved forward end of the skid plate 20 of the power tool beneath the reversely bent forward portions 19 of the lower flanges 14 of the side frame members 10 and 11.

Upon lowering the rear end of the tool to the position shown in Figs. 1 and 2, the upturned forward end of the skid plate 20 is engaged beneath the reversely bent portions 19 of the lower flanges 14 to clamp the tool to the frame.

The rollers 21 and 22 are mounted at a height to support the frame A slightly clear of the work piece so that the guide frame with the tool supported therein is free to roll along the work piece D. By adjusting the guide C so that the shoe portion 26 is at a desired distance from the plane of the cutting blade 40 of the tool B, and then securing the guide frame C in such adjusted position by tightening the thumb screws 37, the frame will guide the blade along a path at a predetermined distance from, and parallel to, the edge of the work piece D.

For locking the frame A to the tool B in the event that it should be desired to make several cuts in succession without removing the tool B from the carriage frame A, a thumb screw 41 (Fig. 4) is screwed into an inwardly and downwardly sloping, threaded hole provided axially through a lug 42 welded to a side of the frame member 11 near its rear end. By screwing the thumb screw 41 inwardly and downwardly to have its inner end bear on the rear end of the skid plate 20 of the power tool B (Fig. 2) the tool will be firmly clamped in the frame A.

While I have illustrated and described a preferred embodiment of the present invention, it will be understood, however, that various changes and modifications may be made in the details thereof without departing from the spirit and scope of the invention as set forth in the appended claims.

Having thus described the invention, what I

claim as new and desire to protect by Letters Patent is as follows:

1. An accessory guide carriage for a portable power driven hand tool having a rotary cutting element adjustably mounted on a skid plate, said carriage comprising a frame, a marginal seat formed therein to receive opposite edges of the skid plate therein, said frame having an opening to receive the cutting element of the tool for free rotation with the tool mounted in said seat, means for releasably securing the skid plate in the seat, support means mounted on said frame for transverse adjustment on said carriage frame, a guide shoe on said support means disposed to engage an edge of a work piece upon which said frame is mounted, and a supporting roller rotatably mounted on said support means in position to provide rolling support for the carriage having a tool portion mounted thereon.
2. An accessory guide carriage for a portable power driven hand tool having a rotary cutting element adjustably mounted on a skid plate, said carriage comprising a frame, a marginal seat formed therein to receive opposite edges of the skid plate therein, said frame having an opening to receive the cutting element of the tool for free rotation with the tool mounted in said seat, means for releasably securing the skid plate in the seat, a pair of parallel support elements mounted for transverse adjustment on said frame, means for retaining said support elements in adjusted position, a guide shoe on said support elements disposed to engage an edge of a work piece upon which said frame is mounted, and a pair of carriage supporting rollers rotatably mounted one on each of said support elements, said rollers being positioned to provide rolling support for said carriage with the tool skid plate mounted in said seat.
3. An accessory guide carriage for a portable power driven hand tool having a rotary cutting element adjustably mounted on a skid plate, said carriage comprising a frame, a marginal seat formed therein to receive opposite edges of the skid plate therein, said frame having an opening to receive the cutting element of the tool for free rotation with the tool mounted in said seat, means for releasably securing the skid plate in the seat, support means mounted for transverse adjustment on said carriage frame, a guide shoe on said support means disposed to engage a side of a work piece upon which said frame is mounted, a supporting roller rotatably mounted on said support means, and a clamp for securing the support means in transversely adjusted position on the frame.
4. An arrangement according to claim 3 wherein the support means comprises a rod slidably inserted in aligned holes in opposite sides of said frame, said clamp comprising a first clamp portion mounted on the frame on one side of a hole for said support rod, a second clamp portion pivotally mounted on said frame on a diametrically opposite side of said hole from said first clamp portion, and means mounted to draw the pivotally mounted second clamp portion toward the first clamp portion to grip the rod in adjusted position therebetween.
5. A guide carriage for a power driven hand tool, said carriage comprising a rectangular frame having spaced apart side portions and spaced apart front and rear portions arranged to enclose an opening to receive a tool element therein, recessed means in said carriage frame for receiving a marginal edge portion of the tool

element, a rod portion mounted transversely of said carriage frame endwise beyond the tool receiving opening therein, a roller journaled in carriage supporting position on said transversely extending rod portion, means for axially adjusting the rod portion in said roller and in said carriage frame, and a guide portion on said rod portion for adjustment therewith, said guide portion being positioned for guiding engagement with a side of a work piece upon which said carriage frame is adapted to be mounted for rolling support by said roller.

6. A guiding device for a power driven hand tool having a skid plate with up-turned forward portion, said device comprising a carriage frame having an opening therein formed to receive and to support a skid plate of a power tool therein, means for receiving the up-turned forward end of the skid plate of a power driven hand tool inserted in said frame to retain said skid plate against displacement, a guide member mounted transversely of and extending laterally from said frame, a roller journaled in frame supporting position on a transversely disposed portion of said guide member within said frame, means for adjusting said guide member transversely of said frame, and an element on said guide member disposed laterally beyond said frame in adjusted position to engage a marginal edge of a work piece when said frame is supported on such work piece by said roller.

7. An accessory guide carriage for a portable power driven hand tool having a rotary cutting element adjustably mounted on a skid plate, said carriage comprising a frame, a marginal seat formed therein to receive opposite edges of the skid plate therein, said frame having an opening to receive the cutting element of the tool for free rotation with the tool mounted in said seat, means for releasably securing the skid plate in the seat, a guide member mounted to extend laterally from said frame, a roller journaled in frame supporting position on said guide member, means for adjusting said guide member transversely of said frame, and a guide shoe mounted on a laterally extending portion of said guide member and positioned to engage a marginal edge of a work piece when said frame is supported thereon by said roller.

8. A guide for a power driven hand tool comprising a frame, said frame comprising a pair of parallel side members of right angle cross sec-

tional shape mounted with a flange of each thereof disposed on the lower side and facing inwardly, an end portion of one of said lower flanges being bent reversely upon itself, to form a tool retaining recess, end members connecting said side members to form a tool receiving enclosure, a pair of rods adapted to be mounted transversely of the front and rear ends respectively of said frame; a pair of rollers mounted for rotation one on each of said transversely extending rod portions between said frame side members, said rollers extending below said frame to provide rolling support therefor, and a laterally adjustable guide portion mounted on said rod portions laterally beyond said frame, said guide portion extending below the level of the bottoms of said rollers to engage a marginal edge of a work piece upon which said frame is supported to guide a tool in said frame along a path disposed a predetermined distance from said marginal edge.

9. A guide carriage for a power driven hand tool; said carriage comprising a frame adapted to mount a power tool thereon, a pair of open end hollow axles mounted to extend transversely of said frame endwise beyond a tool mounted thereon, a roller rotatably mounted on each axle to provide rolling support for said carriage with a power tool mounted thereon, a guide support rod telescopically inserted in the bore of each hollow axle to extend laterally beyond said frame, means for axially adjusting said rod portions in said hollow axles, means for clamping said rods in axially adjusted position in said axles, and a guide portion mounted on said rod portions for adjustment therewith, said guide portion extending below said carriage frame in position to engage a marginal edge of a work piece upon which said carriage frame is adapted to be mounted for rolling support by said rollers.
